UNITED STATES PATENT OFFICE

KENNETH HERBERT BOWEN, OF AUBURN, NEW YORK, ASSIGNOR TO HENRY AND ALLEN, OF AUBURN, NEW YORK, A CORPORATION OF NEW YORK

HEATER FOR WATER-COOLED ENGINES

Application filed July 23, 1928. Serial No. 294,715.

This invention relates to a new and improved heater for the cooling fluid of water-cooled engines.

When an automobile has an engine which is cooled during operation by the circulation of water around the cylinders of the engine and through a radiator, it is preferable during the time of year when the temperature is low to have some means of preventing such water not only from freezing because the freezing of the water is apt to cause damage to the engine, but also from becoming cold because when the engine cylinders are cold it is difficult to start the engine. Of course, it is possible to provide heat in a garage or other storage place for an automobile, but to do so is expensive and a source of difficulty and annoyance.

The main object of my invention is to provide a means whereby the water in the cooling system of an automobile engine may be kept at a substantially predetermined warm temperature by means of electricity, which will not only be effective, but will be convenient and inexpensive.

Another object is to provide a heating means of this character which can be readily connected to a source of current supply and is automatically controlled so that the temperature of the water will never exceed a predetermined degree.

Another object is to provide a heating means of the character described in which the heating coil and the automatic control may be disposed in the water jacket of the engine.

Other objects and advantages relate to the size, shape and arrangement of parts, all as will more fully appear from the following description, taken in connection with the accompanying drawings, in which:

Figure 1 is a side elevation of an automobile engine showing my device installed in the water jacket of the engine.

Figure 2 is a section on line 2—2 of Figure 1.

Figure 3 is a diagrammatic drawing of the wiring system used when the installation is made as shown in Figure 1.

In the drawings, I show my device installed directly in the water jacket of an automobile engine.

The automobile engine —25— has the usual water jacket —26— comprising a header portion —27— and a depending skirt portion —28— adjacent the walls —29— of the automobile cylinder in which is disposed the usual piston —30—. The header —27— is connected by a conduit —31— to the upper portion of a radiator —32—. A second conduit —33— leads from the bottom of the radiator —32— to a pump —34— and thence to the skirt portion —28— of the water jacket —26— through another conduit, not shown.

Referring particularly to Figure 2 I provide a cylindrical tube —35— externally threaded on one end and internally threaded on the other end. Tube —35— is threaded into the skirt —28— adjacent the bottom edge thereof. A resistance coil heater —36— is positioned in tube —35— and is held in place by a cap —37— threaded into the outer end of tube —35—.

A second cylindrical tube —38— externally threaded on one end and internally threaded on the other is threaded into the header —27— of the water jacket —26—. A thermostatic bulb —39— is positioned in tube —38— and is held in place by a plug —40— screwed into the outer end of tube —38—. Plug —40— has a central aperture through which extends the thermostatic tube —41— through and into a conduit —42—. Plug —40— has a laterally extending threaded portion —43— on which is threaded a cap —44—. Conduit —42— carries a double beveled bushing —45— which is positioned between plug —40— and cap —44— to insure the retention of the water in the header

—27—. The conduit —42— extends to a thermostatic switch —46— which may be of any desired type. Switch —46— is positioned on dash-board —47— of the vehicle. 5 Switch —46— is connected through a suitable cable —48— to a fuse box —49— carrying the usual fuse —50—. A socket —51— is positioned on dash-board —47— below fuse box —49— and is connected by a suitable 10 cable —52— to the fuse box —49— and to the electrical heater —36—. The thermostatic switch —46— is normally closed when the automobile engine —25— is not operated so that when a lead, not shown, from any 15 convenient source of potential, not shown, is inserted in socket —51— the current will pass from socket —51— to cable —52—, fuse box —49—, cable —48—, switch —46—, fuse —50—, cable —52— and heater —36—.

20 It will be understood that cylinders —35— and —38— are in communication with water jacket —27— so that heater —36— and thermostatic bulb —39— are at all times immersed in the water which is in water jacket 25 —26—.

When current is passing through heater —36— the heat units so generated by the heater —36— will be transferred to the water in the water jacket —26—. This heat transfer will be continued until the temperature of the water becomes sufficiently high to cause the thermostatic switch —46— to open and break the circuit through heater —36—. The circuit so broken will remain open until 35 the temperature of the water in the water jacket —26— has dropped sufficiently to cause the thermostatic switch to again close and complete the circuit when the heating of the water will then be continued.

40 Altho my device will function irrespective of the relative positions of the heater —36— and thermostatic bulb —39— to each other and to the water jacket —26— I have discovered that the most efficient location of 45 the parts of my device with reference to each other and to the water jacket —26— is to have the heater —36— in the lower part of the water jacket —26— and the thermostatic bulb in the upper portion of the water jacket 50 —26—. This is because of the fact that warm water will rise in water jacket —26— due to the thermosiphon action and with the last described disposition of parts the colder water in the water jacket —26— will receive the heat directly while the thermostatic control of the heater —36— will be effected by the warmest water in the radiator —26—.

55 It will be understood that my device will function without the use of a fuse box and fuse altho I prefer to use them as an assurance of safety during the operation of the device.

It will also be understood that any particular type of electrical heater and any particular type of heat control switch is not essen-

tial to the spirit of my invention nor is the exact location of these parts of the device.

It will also be understood that my device can be used with any type of apparatus which has a water cooling system and that the size, shape and arrangement of the different parts of my device may be varied to adapt them to different conditions, for altho I have shown and described a specific structure and form of part as an exemplification of an embodiment of my invention I do not desire to restrict myself to the exact shape, form or relation of parts as various changes may be made within the scope of the appended claims.

I claim:

1. In a water cooled engine having a water jacket surrounding the cylinders thereof, a casing projecting from the jacket and having its inner end secured to the lower portion of the jacket, an electric heater disposed in the casing and adapted to be connected to a source of potential, means for connecting such heater to such source, a second casing projecting from the jacket and having its inner end secured to the upper portion of the jacket, and heat controlled means arranged in the second casing and actuated in accordance with the temperature of the water in the top portion of the water jacket for breaking such connecting means.

2. In a water cooled engine having a water jacket surrounding the cylinders thereof, casings detachably connected to the water jacket and projecting from the upper and lower portions thereof, an electric circuit, an electric heater interposed in said circuit and arranged in the lower one of said casings, and a thermostatic switch interposed in the circuit and arranged in the upper one of said casings.

3. In a water cooled engine having a water jacket surrounding the cylinders thereof, upper and lower casings projecting from the water jacket and each having its inner end secured to the water jacket, an electric circuit, an electric heater interposed in said circuit and arranged in the lower casing, and a thermostatic switch interposed in the circuit and arranged in the upper one of said casings.

4. In a water cooled engine having a water jacket surrounding the cylinders thereof, upper and lower casings projecting from the water jacket, each casing being of tubular form and having threads at its outer end, threaded caps connected to the outer ends of said casings, an electric circuit, an electric heater interposed in said circuit, arranged in the lower casing and supported by the cap of that casing, and a thermostatic switch interposed in the circuit, arranged in the upper casing and supported by the cap of the latter.

5. In a water cooled engine having a water jacket surrounding the cylinders thereof, upper and lower casings projecting from the

water jacket, each casing comprising a tubular member having threaded ends, the inner ends of the casings having threaded connection with the water jacket, threaded caps
5 closing the outer ends of the casings, an electric circuit, an electric heater interposed in said circuit, arranged in one of said casings, and supported by the cap of the latter, and a thermostatic switch interposed in the circuit, arranged in the other casing, and supported by the cap of the latter.

In witness whereof I have hereunto set my hand this 18th day of July, 1928.

KENNETH HERBERT BOWEN.
